UNITED STATES PATENT OFFICE.

EDWIN L. WIEGAND, OF CANAL DOVER, OHIO.

PROCESS OF PRODUCING ELECTRICAL HEATING DEVICES.

Specification of Letters Patent. Patented Apr. 20, 1915.

1,136,076.

Original application filed January 9, 1914, Serial No. 811,262. Divided and this application filed July 13, 1914. Serial No. 850,746.

To all whom it may concern:

Be it known that I, EDWIN L. WIEGAND, a citizen of the United States, residing at Canal Dover, in the county of Tuscarawas and State of Ohio, have invented a certain new and useful Improvement in Processes of Producing Electrical Heating Devices, of which the following is a full, clear, and exact description, reference being had to the accompanying drawings.

This invention relates to a process of producing electrical heating devices and has for its general purpose the provision of a process which will enable a heating device or appliance to be produced in a particularly effective manner, reducing the cost of production and increasing the efficiency of the device or appliance.

Generally speaking the invention may be defined further and more generally as consisting of the combinations of steps and manipulations recited in the claims hereto annexed and illustrated in the drawings accompanying and forming a part hereof, wherein:

Figure 1 is a vertical sectional view taken through the center of a heating device and illustrating the mode of use of one form of apparatus whereby the process in question can be practised; Fig. 2 is a perspective view of the tool, or that portion of the apparatus on which the conductor is wound and supported prior to its application to the heating device; Fig. 3 is a perspective view of the base plate of the heating device prior to the application of the conductor thereto; Fig. 4 is a perspective view of the stripping plate and Fig. 5 a similar view of the base of the tool; Figs. 6, 7 and 8 are sectional views taken through the heating element and the coöperating parts, illustrating the successive steps in the process of producing the heating device; Fig. 9 is a transverse, cross-sectional view through the complete heating device; and Fig. 10 is a detail in perspective of one of the pins on the tool base.

The present application is a division of my copending application filed Jan. 9, 1914, Serial No. 811,262.

In carrying out the process illustrated and

claimed herein, I first apply to the base for a heating device a layer of material, preferably cementitious, such as is ordinarily employed for the support of the conductors of such devices. For this first layer, the material may be in a sufficiently fluid condition to enable it to be applied by pouring. This layer is then dried, preferably by specially arranged surface-plates, heated preferably by steam. After this preliminary layer has been so dried, a second layer, preferably of the same kind of material, is applied to the article and is partially dried in the manner described in connection with the first layer, until it is reduced to a plastic or putty-like consistency, which renders it capable of receiving and retaining the conductor. The conductor is given a form which will enable it to perform its heating function in an efficient manner. It is then introduced (preferably by the mechanism to be described hereinafter) into the plastic second layer, the ends of the conductor being suitably arranged for connection with the source of current supply. After the introduction of the conductor into the plastic material, the material is dried, preferably in the manner described hereinbefore in connection with the first layer. A final layer of the cementitious material is then applied and this final layer is then partially dried—to put it in condition to receive a pressure plate, which pressure plate is subjected to a very high pressure, such as is obtained by the use of a hydraulic press, with the result that a very intimate contact is obtained between the conductor and the surrounding material, producing a homogeneous mass and adapting the exposed surface of the material for the reception of a plate which serves to keep in place the heating element proper (consisting of the conductor and the surrounding material) as well as covering this element for the purpose of protection. After the pressing operation, the heating element still contains a certain amount of moisture, which is driven out by a preliminary heating in a drying kiln, after which the whole is subjected to a heating action sufficient in temperature and duration to vitrify the material. Or instead of adding

the first two layers successively, I may at the first operation introduce enough plastic cementitious material both to cover and insulate the heater base and to embed the conductor, in which case I dry the whole to the proper degree necessitated by the requirements of the lower or insulating layer, and then by sprinkling or moistening reduce the upper part of the mass to the consistency necessary to the reception and retention of the conductor. The drying, application of the final layer, pressing, and vitrification proceed as before and the advantage of this modification is the entire homogeneity of the first and second layers.

In carrying out my improved process I may and as at present advised preferably will employ a machine of the character shown in the drawings, which machine will now be described in connection with reference characters.

1 denotes a bed of any suitable size and outline, said bed being designed to support the moving parts of the apparatus and the device to which the conductor is to be applied. For convenience of description, that part of the heating device which receives the heating element proper will be referred to as the "base." In the drawings, for purposes of illustration, the heating device is shown as forming part of a sad iron. This base is indicated at 2 and is shown as located on the bed in any convenient manner, as by means of gages 3 shown as secured to the plate 4. Suitably mounted above this bed is a vertically movable arm 6, to which a ring 13 is pivoted upon horizontal trunnions 14 one of which is here shown as provided with a radial arm 38 adapted to engage either of the latches 39 or 40, whereby it may be retained with either side uppermost. The end of the arm 6 is preferably provided with a handle 12. A turret 17 is secured in this ring in any suitable manner as by the plate 18, the turret having a longitudinal bore 19. On the top of the turret there is secured the tool on which the conductor is wound to give it the desired shape and on which it is supported until applied to the previously prepared base 2. The tool comprises a base plate 20 having projecting therefrom a series of pins 21, the pins being arranged to support the conductor while it is being wound and to give to said conductor the desired symmetrical shape which will best adapt it for use in the particular heating device of which it is to form a part. Each pin is preferably of the shape shown particularly in Fig. 11 and has an upper reduced end 22, which reduced end projects beyond the stripping plate (to be described hereinafter), such reduced end being provided with a substantially vertical narrow

face 23 and the top of this reduced end being tapered to make a recess of correspondingly small dimensions when inserted in the cementitious material in the base 2.

24 denotes a stripping plate which is mounted on the pins 21, said pins projecting through apertures 25 in the plate and having their reduced ends 22 projecting thereabove.

The base plate 20 is shown as provided with an aperture 26 for the reception of the stud 27. This stud is shown as provided with a threaded aperture for the reception of a screw 28 which is placed within a recess 29 in the top of the stripping plate 24. The end of the stud 27 projects into the bore 19 and is preferably cupped, as shown at 30, 80 for the reception of the rounded end of a push rod 32, whose other end is preferably pivoted to a lever 33 fulcrumed to the arm 6 in any suitable manner as by the bracket 34.

With this construction it will be seen that the turret 17 is reversible about the axis of the trunnions 14 and also rotatable about the axis of the ring 13, the former permitting it to be faced upwardly to receive the windings, the latter permitting the operator to swing or rotate it during the application of the windings thereto. In use the turret is first located with the tool 20 facing upwardly, and the stripping plate 24 applied thereto with its stud 27 projecting into the bore 19. The conductor 35 is next wound upon the projecting tips of the pins 21 according to the design found most satisfactory in practice, taking into consideration rapidity of winding and uniformity of heating. I much prefer a conductor of the ribbon type, and the pins are best arranged so that this conductor is wound around the vertical faces 23 of the pin ends. The ends of the conductor are passed through bushings 36, which are previously inserted into holes 37 in the stripping plate 24, and through the aligned holes 38 in the base plate 20. After the conductor has been wound upon or applied to these pins the turret is preferably locked to the ring by suitable means (not shown) and is then inverted to the position illustrated in Fig. 1.

The base is prepared for the reception of the conductor by applying thereto the initial layer 52 of the cementitious material, this material being introduced in a more or less fluid condition. The layer is then dried in any convenient manner, as by the application of the steam heated plate 53 thereunder. A second layer 54 of plastic material is then applied to the base, and this layer is partially dried, as by means of the steam heated plate 53, until it is in a plastic or putty-like condition,—when its consist-

ency adapts it best for the reception and retention of the conductor. Or I may apply at one operation a quantity of cementitious material sufficient for both layers and dry the 5 whole to the degree sufficient for the body of the material, subsequently softening the upper part by sprinkling so as to receive the conductor. In any case the fluidity of the first layer is preferably such as barely to 10 cause it to seek its level, and to assure its coming into intimate contact with all parts of the casing interior.

The base prepared as above described, is introduced beneath the turret 17, which is 15 thereupon depressed by means of the handle 12 so as to embed the conductor in the plastic material. The push rod 32 is next applied and the lever 33 depressed, thereby holding down the stripping plate and raising the 20 arm 6, thus withdrawing the pins from the conductor, leaving the latter embedded in the plastic material. Owing to the tapered ends 22 of the pins, the openings which are 25 made in the plastic material will be of small extent and will not interfere with the production of a homogeneous filling for the base 2 and the intimate contact between such filling and the conductor. The stripping plate is then removed and the plastic material is dried, preferably by the use of one 30 of the plates 53. A third layer 59 preferably of cementitious material is then applied to the base 2, covering the conductor, and as this final layer is dried sufficiently so 35 as not to be sticky or tacky a pressing plate 61 of proper shape, surface, and dimensions is applied to the surface and forced powerfully thereagainst by suitable means such as a hydraulic press, the opposed members of 40 which are indicated conventionally at 62 and 63, Fig. 9. The result of this pressing action is to secure a very intimate contact between the conductor and the surrounding cementitious material, producing a solid, 45 homogeneous mass, the upper surface whereof is adapted to receive a cover plate 64 which will preferably form a part of the heating device, and serve to keep in place the heating element (consisting of the conductor and the surrounding cementitious 50 material). This compacting also expels all air for both from the mass thus improving the conductivity for heat, reduces its hydroscopic tendency, and prevents change in 55 volume of the mass upon swiftest action, which is a very important matter owing to the necessity of having the cavity entirely filled with material and still being able to secure the cover tightly in place. After the 60 pressing operation, the heating element still contains some moisture, which is driven out by a preliminary heating operation, as in a drying kiln, after which this element is sub-

jected to a temperature sufficiently high and of sufficient duration to vitrify the mass in 65 which the conductor is embedded.

While I have necessarily shown and described in detail the manner whereby an electrical heating device may be produced by means of my process and apparatus, it 70 will be evident that these details may be departed from, more or less, without avoiding the spirit of my invention; hence I do not propose to be limited to such details, except as they may be positively included in the 75 claims hereto annexed or such limitation may be rendered necessary by the state of the prior art.

Having thus described my invention what I claim is:—

1. The process of making electrical heating devices which comprises providing a suitable base with a bed of cementitious material having its lower part of greater hardness and dryness than its upper part; inserting 80 a heat producing element into such upper part; covering said element with cementitious material; partially drying the whole mass; compacting the entire mass by the application of pressure and vitrifying 85 the same by the application of heat.

2. In a process of making electrical heating devices, the steps which consist of providing a suitable base with a bed of plastic cementitious material, inserting into said 95 bed a previously formed conducting coil, covering said coil with plastic material, abstracting moisture from said material, compacting said material, and vitrifying said material.

3. The process of manufacturing electrical heating devices which comprises providing a suitable base with a mass of cementitious material whose outer part is softer and more plastic than its inner part; embedding an 105 electric conductor in such softer part; applying a covering of cementitious material to said conductor; drying the mass; subjecting the mass to high pressure; and drying 110 and burning the mass.

4. The process of making electric heating devices which comprises applying to a suitable base a mass of plastic cementitious material; drying the same; softening the topmost parts thereof for the reception and retention of an electric conductor; applying a covering mass of plastic cementitious material; drying the whole mass; compacting the entire mass by the application of 115 pressure; and finally vitrifying the same by 120 the application of heat.

5. The process of producing electrical heaters which consist in applying a mass of cementitious material to a suitable base; partially drying the mass; inserting a heat-producing element into the mass; drying the 125

second mass; applying a covering of cementitious material thereto; partially drying the covering; subjecting the mass thus formed to high pressure; heating the mass to drive out the moisture; and finally baking or firing the mass to vitrify the same.

In testimony whereof, I hereunto affix my signature in the presence of two witnesses.

EDWIN L. WIEGAND.
